UNITED STATES PATENT OFFICE.

REINHOLD WEISE, OF NEW YORK, N. Y.

THRILL-POLE.

1,296,145.

Specification of Letters Patent.

Patented Mar. 4, 1919.

Application filed May 21, 1918. Serial No. 235,888.

To all whom it may concern:

Be it known that I, REINHOLD WEISE, a subject of the Emperor of Germany, residing at New York, in the county and State 5 of New York, have invented certain new and useful Improvements in Thrill-Poles, of which the following is a full, clear, and exact specification.

This invention relates to amusement devices especially designed to be employed as a part of a circus performance, and has for its object to provide a novel device for entertaining and thrilling the audiences at such performances. Another object is to 15 provide a device of the character described which may be knocked down for convenient shipment from place to place along the route of a circus or other performance, and which may be quickly set up for use at each stand. 20 The invention consists essentially of a pole adapted to be secured in upright position so that acrobatic performances may be enacted on its upper end portion, during which the pole may have the appearance of 25 falling with the acrobat whose life will seem to the audience to be in jeopardy. Mechanism is provided, however, for gradually retarding the fall of the pole which is brought to rest before the feet of the performer touch the ground.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout 40 the several views:—

Figure 1 is a side elevation of a thrill pole device constructed substantially in accordance with this invention and erected for use at a performance.

Fig. 2 is an end elevation of the same.

Fig. 3 is a side elevation of the device showing the position of the pole when at the end of the fall.

Fig. 4 is a side elevation of the supporting 50 frame for the pole drawn to a larger scale.

Fig. 5 is a longitudinal vertical section through said supporting frame and pole.

Fig. 5^a is a section on line V—V of Fig. 5.

Fig. 6 is a side view of one of the main 55 pieces of the frame as it appears when taken apart for shipment.

Fig. 7 is a longitudinal section through the joint in the pole.

Fig. 8 is a cross section on the line VIII—VIII of Fig. 7.

Fig. 9 is a detailed view of one of the detachable end pieces of the frame, showing the mortise and tenon joint between it and the main piece of the frame with the parts separated.

Fig. 10 is a detailed perspective view of one of the braces which are detachably fastened to said end pieces of the frame and the arcuate members.

Fig. 11 is a section on the line XI—XI of Fig. 5.

Fig. 12 is a detailed view of the sleeve coupling the inner ends of the arcuate members.

Fig. 13 is a detailed side elevation of one 75 of said arcuate members detached from the frame.

Fig. 14 is an end view of one of the main pieces of the frame, as shown in Fig. 6, showing the lateral brace folded up as in 80 said figure.

Fig. 15 is a detailed view of the tie-piece for retaining the upper end portions of the journal members of the frame in properly spaced relation, and

Fig. 16 is a section on the line XVI—XVI of Fig. 5.

The pole is preferably about thirty feet long, but this dimension may of course be varied if desired. For convenience in shipping from place to place, the pole is made in detachable sections 1 and 2. The upper section 1 is connected to the lower section 2 by a dowel pin 3, see Figs. 7 and 8. In order to make the pole springy without being brittle, it is made up of a plurality of longitudinal pieces 4 which may be glued or otherwise secured together, and around said laminated pole is wrapped or wound a tape covering 5 which provides a rough surface 100 on which the hands of the performer will not slip.

The lower section 2 of the pole is square at the bottom and set into a heavy metal boxing 6, best shown in Figs. 5 and 5^a, said 105 boxing serving as a counterweight when the pole swings or falls. The pole is secured in said boxing by means of the bolts 7. The lateral pieces of the boxing extend above the other pieces thereof and are provided 110 with projecting pivot lugs 8 which are journaled in notches 9 in the upper ends of the

upright portions 10 of the main frame pieces 11. The pivot lugs 8 preferably engage wear pieces 80 in notches 9. Said main frame pieces, (of which there are two alike, one arranged at each side of the base of the pole), 5 also comprise horizontal members 12 extending to each side of the base of the upright members 10 and to which the latter are braced by inclined braces 13. The two main frame pieces are seated the proper distance apart in a notch 14 in a central transverse bed-piece or sleeper 15 to which they are detachably connected by braces 16, each hinged as at 17 at its upper end to one of the 10 upright portions 10 of a main frame piece and carrying one leaf 18 of a hinge the other leaf 19 of which is fastened to the end portion of said sleeper 15. These hinge leaves are detachably connected together by a 15 movable pintle 20 which is attached to a cord or chain 21 fastened to the brace 16. When the frame is knocked down, the braces 16 are folded up against the upright members 10 of the main frame pieces, as shown 20 in Figs. 6 and 14.

Detachable end pieces 22 are connected to the ends of the horizontal members 12 of the main frame pieces by mortise and tenon joints 23 best shown in Fig. 9. These end pieces (of which there are two alike at each end of the frame) are seated in properly spaced notches 24 in end sleepers 25, as best 25 shown in Fig. 2. Lugs 26 on said end pieces abut against the inner faces of the end sleepers for preventing them from sliding inward along the end pieces. The mortise and tenon joints between said end pieces and the main frame pieces have overlapping portions 27 at the top and underlapping portions 28 at 30 the bottom for making a strong and rigid joint. These joints are held together and the end sleepers 25 retained in proper position on the end pieces by guy ropes 29 running from the ends of the end pieces 22 to 35 the upper ends of the upright portions 10 of the main frame pieces, said ropes being attached to hooks 30 on the end pieces and to hooks 31 on the upright pieces, and being adjustable by the provision of the sheave blocks 32. Other guy ropes 33 are connected to the hooks 31 and to hooks 34 on the lower ends of the braces 16 and provided with sheave blocks 32^a for retaining the two upright members 10 properly spaced apart 40 at the sides of the base of the pole. The upper ends of said upright members are tied together with a notched strip 35 interlocking with notches 35^a in projections 35^b at one side of the said upper ends of the upright members, as best shown in Fig. 15. This strip 35 may be disengaged from the notches in the upright members when the frame is to be knocked down.

Between the central sleeper and the end sleepers, the horizontal portions 12 of the

main frame pieces are tied together and properly spaced apart by notched strips 36, the notches 36^a whereof interlock with notches 36^b in the upper edges of said horizontal portions 12. The strips 36 also have notches 37 in their upper edges in which are seated arcuate members 38 and 39 which rise from the center of the main frame at both sides and conform substantially to the arc of the bottom end of the pole when the latter is swung on its pivots, as indicated in Figs. 3 and 5. Each of said arcuate members comprises a pair of side pieces 40 arranged parallel to each other and spaced apart side by side by cross pieces arranged at suitable intervals. The right hand arcuate member 38, as viewed in Figs. 1, 3, 4 and 5, has two cross pieces 41 connecting the intermediate portions of its side pieces 40, and another cross piece 42 at the upper ends of said side pieces. This cross piece 42 has a groove or notch 43 in its upper edge to receive the pole when the latter has been fully swung down to the position shown in Fig. 3. The left hand arcuate member 39 has a plurality of 90 cross pieces 44 connecting its side pieces 40 and arranged at short intervals apart throughout the greater part of the length of said side pieces, as best shown in Fig. 5. There is also an end cross piece 45 at the upper end of the arcuate member 39.

The series of cross pieces 44 on the left hand arcuate member 39 coöperate with a pawl 46 on the bottom end of the pole, also shown in Fig. 5. Said pawl is connected 100 to the pole by a flexible piece of cloth, leather, or other suitable material 46^a which permits it to yield as it passes said cross pieces. As shown in dotted lines in Fig. 5, the pawl 46 enters between each pair of 105 adjacent cross pieces 44 and as it snaps past each successive cross piece the fall of the pole is gradually broken, so that it finally comes to rest in a horizontal position, as shown in Fig. 3, without any jar 110 being produced when said pole reaches the notched cross piece 42 at the upper end of the right hand arcuate member.

Detachable braces 47 are connected to the upper ends of the side pieces of the 115 arcuate members and the corresponding end pieces of the frame preferably by hinges 48 with removable pintles 49 attached to cords or chains 49^a secured to the braces, as best shown in Figs. 9 and 10. 120

The pole may be fastened in upright position, as in Fig. 1, by means of a rope 50 connected at one end to the right hand side of the base of the pole and running through sheave blocks 51, 52, 53 and 54 attached respectively to the central sleeper 15, the right hand one of the tie strips 36, the notched cross piece 42, and the end sleeper 25, said rope being detachably fastened to said end sleeper, as by the rope holder 55. 125

When the proper time arrives in the performance for the pole to fall, the rope 50 is unfastened from the holder 55, whereupon the weight of the acrobat's body when extended at the left of the upper end of the pole, as indicated in Fig. 1, will overcome the counterweight boxing 6 at the lower end of the pole and cause said pole to swing on its pivots 8 to the horizontal position shown in Fig. 3. During this movement of the pole, the fall will be gradually broken by the pawl 46 on the pole snapping past the cross pieces 44 on the right hand arcuate member, as already explained.

In order to give a sudden start to the fall of the pole and thus increase the thrill derived by the audience viewing the performance, a rope 56 is attached to the left hand side of the lower end of the pole and passed through a sheave block 57 attached to a hook 58 on the upper cross piece 45 on the left hand arcuate member. This rope 56 is attached at its other end to a sheave block 59, Fig. 5, through which another rope 60 is passed, said latter rope being also passed through a sheave block 61 fastened to a hook 62 on the right hand end sleeper and adapted to fasten to a rope holder 600. By pulling on the rope 60, the blocks 59 and 61 will be drawn closer together, thus drawing on the rope 56 and swinging the pole over to the right if the rope 50 has been unfastened. The ropes 56 and 60 also serve to control the return of the pole to vertical position after it has been swung down to horizontal position. After the performer lets go of the pole, the counterweight would be apt to swing it up again to vertical position with a jerk were it not for the ropes 56 and 60 which may be paid out gradually so as to insure the easy return of the pole to its vertical position.

Referring again to the arcuate members 38 and 39, they are fastened to the horizontal members of the main frame by bolts or rods 63 passing through said horizontal members and through lugs 64 depending from said arcuate members, as best shown in Figs. 5 and 11. The lower ends of said arcuate members are connected by a sleeve coupling 65, Figs. 5 and 12, which may be permanently secured as at 66 to one member and have sliding engagement with the other member. These connections together with the cross pieces 36 and the braces 47 serve to support the arcuate members rigidly in position for use. At the same time, the parts may be quickly taken apart when it is desired to move the device from one place to another, the cross pieces 36 having no permanent fastening means but simply resting in the notches in the horizontal portions 12 of the frame and being retained therein by the arcuate members 55 resting thereon when the frame is erected.

Having thus described my invention, what I claim as new and desire to secure by Letters Patent of the United States is:—

1. The combination with a supporting frame, of a pole pivoted to swing on said frame, means for normally holding the pole in raised position, and means for gradually breaking the fall of the pole when it is swung down on its pivots. 70
2. The combination with a supporting frame, of a pole pivoted to swing on said frame, and a pawl and ratchet device carried by the frame and the lower end of the pole for gradually breaking its fall when it is swung down on its pivots. 75
3. The combination with a supporting frame, of a pole, means on the frame for normally supporting said pole in raised position, and means for breaking the fall of the pole from raised to lowered position. 80
4. The combination with a supporting frame, of a pole pivoted to swing on said frame, an arcuate member on the frame having a series of spaced abutments, and a flexibly mounted pawl on the lower end of the pole to engage said abutments for gradually breaking the fall of the pole as it is swung down on its pivots. 90
5. The combination with a supporting frame, of a pole pivoted to swing on said frame, a counterweight on the lower end of the pole, an arcuate member on the frame having a series of spaced abutments, and a flexibly mounted pawl on the lower end of the pole to engage said abutments for gradually breaking the fall of the pole as it is swung down on its pivots. 95
6. The combination with a supporting frame, of a pole pivoted to swing on said frame, a rope attached to the lower end of the pole and operatively engaging the frame for normally holding said pole in raised position, and means for gradually breaking the fall of the pole as it is swung down on its pivots. 105
7. The combination with a supporting frame, of a pole pivoted to swing on said frame from vertical to horizontal position, means for gradually breaking the fall of the pole, and a stop on the frame to be engaged by the pole when it reaches a horizontal position. 110
8. The combination with a supporting frame, of a pole mounted on said frame to swing thereon from raised to lowered position, and a covering of adhesive tape wound about said pole for the purpose specified. 120
9. The combination with a supporting frame, of a pole mounted on said frame to swing thereon from raised to lowered position, and an adhesive covering for the pole for the purpose specified. 125
10. The combination with a supporting frame, of a pole pivoted thereon, said frame comprising upright members supporting the 130

5 pivots and arranged at opposite sides of the bottom end of the pole, longitudinal members extending in opposite directions at the bases of said upright members, and lateral braces extending at the sides of said upright members.

10 11. The combination with a pole, of a knockdown frame for supporting the same, said frame comprising parallel main frame pieces having central upright members and oppositely extending horizontal members, a central sleeper arranged below said main frame pieces, and braces between said upright members and the end portions of said 15 sleeper.

20 12. The combination with a pole, of a knockdown frame for supporting the same, said frame comprising parallel main frame members having upright pieces and oppositely extending horizontal pieces, a transverse sleeper below said main frame members, and braces hinged at one end to said upright members and detachably connected to the sleeper at their other ends.

25 13. The combination with a pole, of a knockdown frame for supporting the same, said frame comprising parallel main frame members having upright pieces for connection to the pole and oppositely extending horizontal members, a central transverse sleeper below said upright pieces, and end sleepers arranged transverse for supporting the ends of said horizontal members.

30 14. The combination with a pole, of a knockdown frame for supporting the same, said frame comprising parallel main frame members having upright pieces for connection to the pole and oppositely extending horizontal members, detachable end pieces at the ends of said horizontal members, a central transverse sleeper below the upright members, and end sleepers arranged transversely below said end pieces.

35 15. The combination with a pole, of a knockdown frame for supporting the same, said frame comprising parallel main frame pieces having upright members for connection to the pole and oppositely extending horizontal members, and detachable means 40 for tying said parallel frame pieces together.

45 16. The combination with a pole, of a knockdown frame for supporting the same, said frame comprising parallel main frame pieces having upright members for connection to the pole and oppositely extending horizontal members, means for detachably connecting said horizontal members together, and means for detachably connecting the 50 upper end portions of said upright members together at one side of the connections to the pole.

55 17. The combination with a pole, of a knockdown frame for pivotally supporting

60 said pole, said frame comprising parallel main frame pieces having upright members for supporting the pivots of the pole and oppositely extending horizontal members, an arcuate member detachably connected to said horizontal members and rising above the 65 same in an arc parallel to the arc of movement of the lower end of the pole, a series of spaced abutments on said arcuate member, and a pawl flexibly mounted on the lower end of the pole to engage said abutments for the purpose specified.

70 18. The combination with a pole, of a knockdown frame for pivotally supporting said pole, said frame having parallel horizontal members, an arcuate member extending 75 above said horizontal members and disposed in an arc parallel to the arc of movement of the lower end of the pole, detachable tying pieces having notches in their lower edges to engage the parallel horizontal members, and notches in their upper edges to engage said arcuate member and means for detachably connecting said arcuate member to the horizontal members.

80 19. The combination with a pole, of a knockdown frame for pivotally supporting the pole, said frame having horizontal members arranged at opposite sides of the pole, arcuate members arranged parallel to the arc of movement of the lower end of the 85 pole, and detachable braces between the ends of said arcuate members and the ends of the horizontal members.

90 20. The combination with a pole, of a knockdown frame for pivotally supporting the pole, said frame having horizontal members arranged at opposite sides of the pole, detachable end pieces at the ends of the horizontal members, arcuate members arranged parallel to the arc of movement of 95 the lower end of the pole, and detachable braces between the ends of said arcuate members and said end pieces.

100 21. The combination with a pole, of a knockdown frame for pivotally supporting the pole, said frame having horizontal members arranged at opposite sides of the pole, and central upright members rising from 105 said horizontal members for supporting the pivots of the pole, transverse sleepers at the ends of said horizontal members, and guy ropes running from said sleepers to the upper end portion of said upright members.

110 22. The combination with a pole, of a knockdown frame for pivotally supporting the pole, said frame having horizontal members arranged at opposite sides of the pole, and central upright members rising from 115 said horizontal members for supporting the pivots of the pole, a transverse sleeper arranged below the horizontal members directly under said upright members and extending at opposite sides of the frame, and

guy ropes running from the upper end portion of the upright members to the outer end portions of said sleeper.

23. The combination with a pole, of a knockdown frame for pivotally supporting the pole, said frame having horizontal members arranged at opposite sides of the pole and central upright members rising from said horizontal members for supporting the pivots of the pole, detachable end pieces having mortise and tenon joints with the ends of the horizontal members and forming continuations thereof, end sleepers having notches to receive said end pieces, and guy ropes running from the end of said sleepers to the upper end portions of said upright members for the purpose specified.

24. The combination with a pole, of a frame for supporting the same, said frame

having horizontal members arranged at opposite sides of the pole and central upright members rising from said horizontal members for supporting the pivots of the pole, arcuate members extending from below the pivots of the pole parallel to the arc of movement of said pole, and ropes fastened to the lower end of the pole and running over the upper end portion of said arcuate members for the purpose specified.

25. The combination with a wooden pole, of a metal boxing in which the lower end of the pole is secured, pivot lugs on the upper end portion of the boxing, and a frame having supporting journals for said pivots.

In testimony whereof I have signed my name to this specification.

REINHOLD WEISE.
